UNITED STATES PATENT OFFICE.

FRANKLIN W. BROOKS, OF NEW YORK, N. Y.

LEAD SEAL.

SPECIFICATION forming part of Letters Patent No. 595,989, dated December 21, 1897.

Application filed March 22, 1897. Serial No. 628,724. (No model.)

To all whom it may concern:

Be it known that I, FRANKLIN W. BROOKS, a citizen of the United States, residing at New York, in the county of New York and State 5 of New York, have invented certain new and useful Improvements in Lead Seals; and I do hereby declare the following to be a full, clear, and exact description of the invention, such as will enable others skilled in the art to which 10 it appertains to make and use the same.

My invention relates to certain new and useful improvements in lead seals.

It has for its object to secure accurate adjustment within the seal-press in order that 15 the impression made by the dies shall be properly and positively centered and also to secure a comparatively large field for said impressions.

It has also for a further object to secure a 20 more perfect anchor and interlocking of the ends of the shackle-wire; and with these ends in view my invention consists in the peculiar construction and arrangement of soft-metal body and shackle-wire, as hereinafter more 25 fully described, and illustrated in the drawings.

In order that those skilled in the art to which 30 my invention appertains may fully understand the same, I will proceed to describe the construction, arrangement, and advantages 35 of the same, referring by letters to the accompanying drawings, in which—

Figure 1 is a central vertical section of one 35 of my improved seals. Figs. 2 and 3 are similar views of modifications thereof. Fig. 4 is a view similar to Fig. 1, showing the wire anchored in the head or cap. Fig. 5 is a similar view showing another form of anchor for the wire. Fig. 6 is a plan view of one side of 40 the seal after compression. Fig. 7 is a similar view of the opposite side. Figs. 8 and 9 are detail views showing two methods of enlarging or distending the anchor end of the shackle-wire. Fig. 10 is a perspective view 45 of the seal with the form of wire shown at Fig. 8, and Fig. 11 is a similar view showing the use of a wire in the form seen at Fig. 9.

Similar letters of reference indicate like parts in the several figures.

50 The seal proper is composed, preferably, of soft lead having a base *a* of enlarged diameter and adapted to rest against the back wall

of the throat or slot in the ordinary sealing-press in order that the head or cap *b* of the seal shall be properly centered under the upper or movable die of a press, and also for the purpose of presenting a large field or area to receive the impression from the lower or stationary die. This base portion *a* may be of comparative attenuated proportion in cross- 55 section to secure economy in the use of material.

Rising from the base *a* is an annular or ring-shaped platform *c*, and rising centrally from the space within the ring-shaped platform *c* is a shank *d*, terminating in a comparatively thin cap *b*, the diameter of which is substantially equal to the interior of the ring-shaped platform. 60

The shackle-wire *e* has one end thereof cast 70 in the soft metal, and the other end is left free to be wound around the shank *d* after it has been passed through a car-door staple or around or through any package which the seal is designed to protect. It will be seen that 75 the annular space or recess between the interior boundary of the ring-shaped platform *c* and the central shank *d* constitutes a housing or pocket for the retaining-coils of the shackle-wire, so that no unnecessary resistance is offered 80 to the approach and action upon the soft metal of the dies of the sealing-press.

I have shown the anchored end of the shackle-wire secured in position in several distinct ways, any one of which may be employed, though I prefer that shown in Fig. 1, in which the end of the wire passing within the thin base *a* traverses upward through the shank *d* and terminates in a coil or otherwise distended condition horizontally within the 90 cap *b*. It may, however, pass through the ring-shaped platform *c*, thence up through the shank and into the head or cap, as shown at Fig. 2, or directly into the shank and thence up into the head or cap *b*, as shown at Fig. 3, 95 or it may in each case terminate in the shank without extending into the cap, although I prefer that it should terminate within the cap. The wire may, however, pass directly into the head or cap *b* in a straight diametric line, as shown at Fig. 4, so that the anchored terminus may under compression between the dies of the sealing-press be distended 100 through the straightening out of the crimps

bolt-like into the wall of the ring-shaped platform, or the wire may traverse the head or cap diametrically and in an arched or curved line, as shown at Fig. 5, to produce 5 the same result.

It will be observed that the terminus of the anchored end of the wire if extended sufficiently high within the cap *b* will, when the seal is compressed by the action of the seal- 10 press, overlie and interlock with the coils of the opposite end of the wire, which are disposed circumferentially around the shank *d*, and thus increase the difficulty of withdrawing the wire from the soft metal. This diffi- 15 culty may be increased by forming the ends of the wire with serrations or barbs or by crimping the same in the manner well known to manufacturers of lead seals.

While I prefer the exact form shown at Fig. 20 1, it will be observed by reference to Fig. 2 that instead of the annular recess surrounding the shank *d*, intersecting the vertical interior wall of the ring-shaped platform *c*, as shown at said figure, it may merge by a gradual 25 curve with said wall, as shown at Fig. 2, and as a modification of the forms shown at Figs. 1 and 2 I may dispense entirely with the recess surrounding the shank and construct the soft-metal body with the extended 30 base and solid platform with the shank and cap rising from the latter. In this latter construction, however, the ductility of the metal is depended upon to permit of the forcing of the wire coils surrounding the shank into the 35 body of the platform, and for that reason is less desirable than the forms of construction shown at Figs. 1 and 2; but in all cases, however, it will be seen that the advantages of the broad thin base for properly centering the 40 seal within the press and providing ample

area for the clear impression of any suitable data or characters within the metal are secured.

The construction shown in the several figures involve, as is clearly seen, the disposition of the entire amount of metal in such form that the pressure of the dies is applied successively, and thus less power is required than would be the case if the entire resistance is offered at one time. 45

Having described the construction and advantages of my improved seal, what I claim as new, and desire to secure by Letters Patent, is—

1. A soft-metal seal embodying in its organization a comparatively thin and enlarged base portion *a* having rising vertically therefrom a ring-shaped platform *c* of less diameter than the base, a central shank *d* surrounded by a recess or pocket and surmounted 60 by a cap *b*, in combination with a shackle-wire *e*, having one end anchored within the body of the seal and the opposite end adapted to be coiled about the shank *d*, substantially as hereinbefore set forth. 65

2. A soft-metal seal embodying in its organization a comparatively thin and enlarged base *a*, a smaller vertical platform *c*, a central shank *d*, and cap *b*, in combination with a shackle-wire *e* having one end anchored 70 within the soft-metal body and the other adapted to be coiled about the shank *d*, substantially as described.

In testimony whereof I affix my signature in presence of two witnesses.

FRANKLIN W. BROOKS.
